PROTECTION OF THYRATRON IN IMPULSE GENERATING CIRCUITS

Filed Aug. 7, 1944

UNITED STATES PATENT OFFICE

2,438,962

PROTECTION OF THYRATRON IN IMPULSE
GENERATING CIRCUITS

Ernest D. Burlingame, Eggertsville, Robert W. Carlson, Depew, Madison G. Nicholson, Jr., Snyder, and Maxwell C. Scott, Lancaster, N. Y., assignors to Colonial Radio Corporation, Buffalo, N. Y.

Application August 7, 1944, Serial No. 548,460

11 Claims. (Cl. 250--27)

1

This invention relates to thyratron pulse generating circuits and more particularly to circuits of the type described employing an artificial line discharging through a thyratron in response to triggering impulses upon the control electrode of the thyratron.

In circuits of this type difficulties have been experienced in the past arising from failure of the thyratron to de-ionize as and when it should, i. e., immediately after discharging the artificial line. This may cause failure of the apparatus and even its destruction. The reason for this is that the increase in current over and above the normal operating current may not be sufficient to operate protective devices such as fuses or circuit breakers, but is usually sufficient, if it continues for any length of time, to burn out the power transformer.

Moreover, even if the current does not cause failure of operating parts, such a condition must be avoided, because while it remains the apparatus is unable to function normally, i. e., to deliver pulses by discharging the artificial line in response to triggering impulses.

It is an object of this invention to provide apparatus of a class described in which de-ionization of the thyratron will take place unfailingly at the completion of the discharge of the artificial line or within a predetermined time after completion thereof, should de-ionization not take place.

It is a further object of this invention to provide a circuit of the class described which will not be destroyed or rendered inoperative should normal de-ionization of the thyratron not occur after completion of the discharge.

It is still a further object of this invention to provide apparatus of the class described which is simple and economical to construct and unfailing in operation.

It is still further an object of this invention to provide a circuit of the class described which will automatically reset itself to normal conditions upon operation of the protective device.

It is still a further object of this invention to provide a circuit of the class described embodying a relay which will operate to limit the current flow should normal de-ionization of the thyratron not take place and in which the operation of the relay is definitely certain and entirely free from chatter.

Still other objects and advantages of our invention will be apparent from the specifications.

The features of novelty which we believe to be characteristic of our invention are set forth with

particularity in the appended claims. Our invention itself, however, both as to its principles and to its particular embodiments, will best be understood by referring to the specification and accompanying drawing on which the single figure is a circuit diagram of apparatus in accordance with our invention.

Referring now more particularly to the drawing, triggering impulses from a source not shown or described and not necessary for the understanding of our invention, are impressed through transformer 10, which may have primary winding 10a and secondary winding 10b, upon the control circuit of a tube of the thyratron type designated as 11. This tube may have a cathode 11c, control electrode 11g and anode 11a. Its cathode may be connected to ground and its grid through secondary winding 10b of transformer 10 and through a suitable source of bias 20 and biasing potential 9 to ground. The anode 11a may be connected to the input of the artificial line 12 made up of inductances 13 and capacities 14. The common terminal of all capacities may be connected through the output load diagrammatically indicated as resistance 15 to ground although in many cases this may be a transformer.

Since the design and construction of artificial lines having any particular characteristics is well understood in the art, this is not shown or described in detail. The line may be charged from a power source, not shown, through power transformer 16 having primary winding 16a and secondary winding 16b through rectifier 17 which may have cathode 17c and anode 17a and through charging resistance 19 to the artificial line. Filter condenser 18 may be provided from cathode 17c to ground. In normal operation the triggering impulse impressed upon the grid of the tube 11 is sufficient to cause ionization and thus to permit the discharge of the artificial line through the tube 11. As will be understood, the duration and amplitude of the current pulse derived from the artificial line is controlled by the constituents thereof and is independent of the amplitude and duration of the triggering impulses.

When the thyratron is de-ionized the plate voltage may be as high as 5,000 volts, but when the thyratron is ionized this voltage may drop as low as 15 volts, but this may be insufficient to cause de-ionization of the thyratron after the line has discharged. If this happens, the thyratron will remain ionized and will be unresponsive to triggering impulses and the continued flow of heavy current above and beyond that required by normal operation may result in burning out

the power transformer 16. To prevent this we provide a voltage divider which may be made up of resistances 20 and 21 connected from the anode 11a to ground. Resistance 21 may be shunted by condenser 22 and the voltage drop across resistance 21 may be impressed upon the relay tube 23. This may be a tube of the 6J5GT type and may have cathode 23c, control electrode 23g, and anode 23a. Cathode 23c may be connected to ground through resistance 24 and the anode 23a may be connected to one terminal of the relay winding of relay 26, thence to a source of plate voltage; also bleeder resistance 25 may be connected from the source of plate voltage to the cathode side of resistance 24. Front and back contacts 26f and 26b may be provided for relay 26, to be engaged by armature 26a and when the armature 26a is closed on front contact 26f a circuit is established short-circuiting resistance 27 in series with the primary winding 16a of the power transformer. Resistance 27 is chosen to be of such value that it limits the current through the thyatron 11 to a value less than the critical current required to maintain ionization of this tube.

The operation of the circuit is as follows:

Under normal conditions, i. e., when no impulses are being received by the control electrode 11g of the thyatron 11 and the tube is not ionized, the plate voltage upon this tube may be as high as 5,000 volts. Under these circumstances a substantial positive voltage is maintained on the control electrode of tube 23 with respect to cathode, and tube 23 draws full space current, which flows through the energizing winding of relay 26 and holds the armature 26a against front contact 26f thereby short-circuiting resistance 27 and permitting full flow of current through the power transformer, thereby maintaining the artificial line 12 charged. When a triggering impulse is received, the tube 11 ionizes and the artificial line 12 begins to discharge. After it is completely discharged, the voltage upon the anode 11a may drop to as low as 15 volts, but under certain conditions the thyatron may not de-ionize because a sufficient flow of plate current still occurs. This must be reduced still further in order to de-ionize the tube. When the voltage upon the anode 11a drops, the voltage upon the control electrode of tube 23 likewise drops to a very low value in same ratio and this is made sufficient to cause tube 23 to cut off and thereby release armature 26a which may be biased to back contact and, therefore, opens, removing the short-circuit around resistance 27 and inserting this resistance in series with power transformer primary 16a. The value of this resistance is so chosen that it limits the current flowing through thyatron 11 to a value less than the critical value required to maintain ionization. The tube 11 thereupon de-ionizes, current flow through the tube stops, and the plate voltage begins to rise and line 12 begins to charge. As the plate voltage rises, the voltage upon the control electrode 23g of tube 23 rises and this tube again begins to pass current after the control electrode to cathode potential goes above cutoff value, whereupon space current once more flows through this tube. Relay 26 is energized, armature 26a is moved to front contact 26f, resistance 27 short-circuited, and conditions return to normal.

Resistances 20 and 21 are made relatively high so that when the voltage at the plate of the thyatron 11 is at its normal high value, the

current drawn by the grid of tube 23 is kept down to a reasonable value, say a fraction of a millampere. Also, the ratio of resistance 20 to resistance 21 is made relatively high so that only a small portion of the plate voltage of the thyatron is applied to the tube 23. Preferably the tube 23 is operated at zero bias for high positive voltage on the grid, thereby promoting uniformity of operation and protection. Capacity 22 is employed to eliminate the possibility of relay chatter during normal operation of the thyatron 11 where the ionization lasts for only a fraction of a millisecond.

In order to complete the disclosure herein, but not by way of limitation, the following values are given:

Resistance 19	20,000	Ohms
Resistance 20	6	Megohms
Resistance 21	0.47	Megohm
Resistance 24	3,300	Ohms
Resistance 25	27,000	Ohms
Resistance 27	400	Ohms
Inductance 13	5	Microhenries
Capacity 14	0.002	Microfarads (except the terminating capacity which is 0.004)
Capacity 18	1	Microfarad
Capacity 22	0.1	Microfarad

The artificial line employed has a characteristic impedance Z_0 equals 50 ohms.

Electrical length equals one millisecond.

Output pulse length equals 2 milliseconds.

While we have shown and described certain preferred embodiments of our invention, it will be apparent that modifications and changes may be made without departing from the spirit and scope of our invention, as will be clear to those skilled in the art.

In the specification we have explained the principles of our invention and the best mode in which we have contemplated applying those principles, so as to distinguish our invention from other inventions; and we have particularly pointed out and distinctly claimed the part, improvement, or combination which we claim as our invention or discovery.

We claim:

1. In a pulse generating circuit, in combination, a storage element, means for charging said element, a thyatron, having a cathode, a control electrode, and an anode, connected to said element for discharging the same, means for applying triggering impulses to a control electrode of said thyatron, and means operated by the potential difference between the cathode and anode of said thyatron and responsive to failure of said thyatron to de-ionize after said storage element is discharged, for limiting the current through said thyatron to a value less than that required to maintain ionization therein.
2. In a pulse generating circuit, in combination, a storage circuit comprising capacity, a thyatron, having a cathode, a control electrode, and an anode, connected to said storage circuit for discharging the same, means for applying triggering impulses to said control electrode, and means operated by the potential difference between the cathode and anode of said thyatron and responsive to failure of said thyatron to de-ionize after said storage circuit is discharged, for limiting the current through said thyatron

to a value less than that required to maintain ionization therein.

3. In a pulse generating circuit, in combination, an artificial line, means for charging said artificial line, a thyratron, having a cathode, a control electrode, and an anode, connected to said artificial line for discharging the same, means for applying triggering impulses to said control electrode, and means operated by the potential difference between the cathode and anode of said thyratron and responsive to failure of said thyratron to de-ionize after said artificial line is discharged, for limiting the current through said thyratron to a value less than that required to maintain ionization therein.

4. In a pulse generating circuit, in combination, an artificial line, means for charging said artificial line, a thyratron, having a cathode, a control electrode, and an anode, connected to said artificial line for discharging the same, means for applying triggering impulses to said control electrode, and means operated by the potential difference between the cathode and anode of said thyratron and responsive to failure of said thyratron to de-ionize after said artificial line is discharged, for limiting the current through said thyratron to a value less than that required to maintain ionization therein, said last mentioned means comprising a relay and a control tube for operating said relay, said control tube being responsive to the plate voltage of said thyratron.

5. In a pulse generating circuit, in combination, an artificial line, means for charging said artificial line, a thyratron, having a cathode, a control electrode, and an anode, connected to said artificial line for discharging the same, means for applying triggering impulses to said control electrode, and means operated by the potential difference between the cathode and anode of said thyratron and responsive to failure of said thyratron to de-ionize after said artificial line is discharged, for limiting the current through said thyratron to a value less than that required to maintain ionization therein, said last mentioned means comprising a short-circuited resistor in the current supply path for said thyratron and means for inserting said resistor in response to failure of said thyratron to de-ionize after discharge of said artificial line.

6. In a pulse generating circuit, in combination, an artificial line, means for charging said artificial line, said means comprising a power source and a rectifier, a thyratron, having a cathode, a control electrode, and an anode, connected to said artificial line for discharging the same, means for applying triggering impulses to said control electrode, and means operated by the potential difference between the cathode and anode of said thyratron and responsive to failure of said thyratron to de-ionize after said artificial line is discharged, for limiting the current through said thyratron to a value less than that required to maintain ionization therein.

7. In a pulse generating circuit, in combination, an artificial line, means for charging said artificial line, said means comprising a power source and a rectifier and a resistance in series with said power source, a thyratron, having a cathode, a control electrode, and an anode, connected to said artificial line for discharging the same, means for applying triggering impulses to said control electrode, and means operated by the potential difference between the cathode and anode of said thyratron and responsive to failure of said thyratron to de-ionize after said artificial

line is discharged, for limiting the current through said thyratron to a value less than that required to maintain ionization therein, said means comprising a relay arranged to short out said resistance during normal operation and to insert said resistance upon failure of said thyratron to de-ionize after said artificial line is discharged.

8. In a pulse generating circuit, in combination, an artificial line, means for charging said artificial line, said means comprising a power source and a rectifier and a resistance in series with said power source, a thyratron, having a cathode, a control electrode, and an anode, connected to said artificial line for discharging the same, means for applying triggering impulses to said control electrode, and means operated by the potential difference between the cathode and anode of said thyratron and responsive to failure of said thyratron to de-ionize after said artificial line is discharged, for limiting the current through said thyratron to a value less than that required to maintain ionization therein, said means comprising a relay for short circuiting said resistance during normal operation, and a control tube responsive to the plate voltage of said thyratron for operating said relay.

9. In a pulse generating circuit, in combination, an artificial line, means for charging said artificial line, said means comprising a transformer and a rectifier and a protective resistance in series with the primary of said transformer, a thyratron, having a cathode, a control electrode, and an anode, connected to said artificial line for discharging the same, means for applying triggering impulses to said control electrode, means operated by the potential difference between the cathode and anode of said thyratron and responsive to failure of said thyratron to de-ionize after said artificial line is discharged, for limiting the current through said thyratron to a value less than that required to maintain ionization therein, said last mentioned means comprising a relay for short circuiting said protective resistance, a control tube arranged to energize said relay to short circuit said protective resistance when the plate potential of said thyratron exceeds a predetermined value, and a voltage divider connected to the plate of said thyratron for applying to said control tube a portion of the plate voltage of said thyratron.

10. In a thyratron protecting circuit, in combination, a thyratron, having a cathode, a control electrode, and an anode, a power supply for said thyratron, a protective resistance in the circuit supplying current to said thyratron, a voltage divider connected between cathode and anode of said thyratron, a control tube, a connection for applying a portion of the voltage of said voltage divider to said control tube, and a relay in the output circuit of said control tube for short circuiting said protective resistance, said control tube being arranged to open the short circuit around said protective resistance when the plate voltage of said thyratron drops below a predetermined value.

11. In a thyratron protective circuit, in combination, a thyratron, having a cathode, a control electrode, and an anode, a power source for supplying current to said thyratron, and a protective resistance in series therewith, a voltage divider connected between cathode and anode of said thyratron, a capacitor in shunt with a portion of said voltage divider, a control tube, a connection for impressing a portion of the volt-

age across said voltage divider upon said control tube, and a relay in the output circuit of said control tube, the constants of said control tube and its associated circuits being so chosen that said protective resistance is short circuited for values of plate voltages of said thyratron exceeding a predetermined value and in circuit for values less than said predetermined value.
